UNITED STATES PATENT OFFICE

FRITZ BALZER, OF CINCINNATI, OHIO, ASSIGNOR TO THE AMERICAN LAUNDRY MACHINERY COMPANY, OF CINCINNATI, OHIO, A CORPORATION OF OHIO

WASHING MACHINE

Application filed August 21, 1930. Serial No. 476,754.

My invention relates to fabric treating apparatus and particularly to washing and dry cleaning machine cylinders.

The present invention relates to cylinders having radial partitions for the purpose of dividing the cylinder into a plurality of compartments and to a type of cylinder in which the cylinder sheets and doors are of imperforate material and are provided with inwardly extending V shaped perforated portions for admitting water or other cleaning liquid into the cylinder, one side of each V shaped portion being formed by the radial partitions and the other side being formed by a separate member connected to the radial partitions and to the cylinder sheet.

It is one object of this invention to provide a cylinder of such construction that a load or batch of material in any compartment will operate as a valve during the major part of the treating operation by lodging against the perforated areas to close the perforations and thereby trap the treating liquid in the compartment and cause it to remain with the load in the compartment to prolong the treating operation for substantially the entire distance of travel of the compartment in a single rotation of the cylinder.

By such an arrangement, the batch or load in any one compartment is progressively submerged in the liquid at the bottom of the cylinder, is then spread out in the liquid in the cylinder permitting a penetration of the treating liquid, and thereafter crowded with a squeezing action in the presence of the trapped liquid in one corner of the treating compartment. Then, as the particular compartment continues to travel in its path around the central axis of the washing cylinder the batch is lifted by a suitable baffle provided for that purpose and caused to tumble into a pool in another corner pocket of the compartment where further crowding and squeezing action is produced in the presence of treating liquid. As the cylinder continues to rotate, the liquid from the compartment is discharged into the outer tub or casing and an additional supply drawn in, the batch of materials being separated and distributed through the new supply and being subjected

to a sequence of treatment steps as hereinbefore set forth.

Various other objects and advantageous features of my invention may be seen in the following description and one embodiment thereof may be seen in the accompanying drawings wherein similar characters of reference designate corresponding parts, and wherein:

Fig. 1 is a perspective view, partly broken away and partly in section, of a washing machine embodying my invention; Fig. 2 is a sectional view of the machine shown in Fig. 1; Fig. 3 is a detail view of the perforated V shaped inlet to and outlet from the washing machine cylinder; Fig. 4 is a sectional view showing a modified form of cylinder compartment structure; and Fig. 5 is a view similar to Fig. 4 showing a still further modified form of cylinder structure.

Referring to the drawings, I have shown a washing machine consisting of the usual tub or outer casing 1 supported on a suitable frame 2 and provided with an upper opening 3 having a closure 4 and a lower opening 5 having a closure member 6 that takes the form of a sliding apron. When the machine is being unloaded, the closures 4 and 6 are opened whereby the load from an inner rotatable container 7 can slide out through the lower opening 5 and into some form of conveying means if desired. However, the construction of the tub or cylinder 1, constitutes no part of the invention and may be of any desired form.

In accordance with my invention, the container or cylinder 7 which is rotatably mounted within the tub or outer casing 1 comprises end heads 8 that are, in this instance, imperforate although they might be otherwise. An outer cylindrical wall that is made up of sections is secured to the end heads 8 in any desired manner and one edge of each section is secured to the outer edge of a radial partition 9 which extends outwardly from the center of the cylinder and of which there are enough to divide the cylinder into three compartments A, B and C. These partitions extend from end to end of the cylinder and each partition carries on one side thereof a baffle

10 that is more or less of pyramid form and coextensive with the length of the partition to which it is attached.

Such baffles are arranged on the partitions 5 adjacent to but slightly separated from the center of the cylinder at which point the partitions join and serve the purpose of retarding or holding back the work within the cylinder so that instead of simply sliding out 10 wardly along the partition during rotation of the cylinder the work is tumbled so that all parts thereof come in contact with the treating fluid at sometime during the washing or cleaning operation, during which time the 15 work is retained in the cylinder. While each compartment is provided with but one of the baffles, nevertheless this baffle acts in practically the same manner in both directions of rotation of the cylinder.

20 It will be noted that the partitions 9 adjacent their point of connection with the edges of the sections which go to make up the inner cylinder wall are perforated and that perforated plates 11 extend angularly 25 outwardly from the partitions 9 and from a point at which the perforated portions of the partitions end, these plates having their outer edges secured to the opposite edges of the sections which make up the outer cylinder 30 wall. The perforated portions of the partitions 9 and the angularly extending plates 11 form V shaped openings by way of which liquid within any one compartment in the cylinder may travel outwardly into the tub 35 or outer casing or liquid from the tub or outer casing may enter the compartment.

For convenience and as is usual in cylinder construction, the cylinder is provided with doors 12 and 13, the only difference being 40 that each compartment in this instance is provided with such doors whereby work may be placed within each compartment or removed therefrom.

In the operation of this device, the work in 45 any one compartment is subjected to several crowding, squeezing and separating operations in the bath of treating liquid which results in several separate penetrating effects of the treating liquid throughout one revolution. The crowding and squeezing action is brought about by the work tumbling into the corner of the compartment which is first lowered, depending upon the direction of rotation of the cylinder whereby the weight 50 of the work and the centrifugal force tends to extract the treating liquid therefrom. At the same time, the work, by covering the perforated portion of the corner, acts as a valve or closure for the perforations and 55 prevents the escape of treating liquid from the compartment throughout all, or at least the greater portion, of the rotation of the cylinder, whereby the work is subjected to the same treating liquid a number of times.

60 By the use of partitions that are imper-

forate throughout their greater portion and the action of the work on the perforated portion, liquid from any one compartment may not easily enter another compartment to thus carry undesirable materials from one compartment into another. However, liquid from any compartment may discharge into the outer tub or casing at certain points in the rotation of the cylinder and the undesirable material be allowed to settle into or be 70 gathered in traps such as are normally used with washing machines of this type. Likewise, treating liquid from the outer tub or casing will have ample time to enter the compartment whereby the work therein may be 75 subjected to a fresh supply.

Referring to Figures 4 and 5 of the drawings, I have shown modified forms of cylinders wherein the partitions are so connected at their adjacent edges or so formed that the 80 angle of the partition will be increased so as to more efficiently unload the machine through the lower apron or door 6 of the outer tub or casing. In Fig. 4 the adjacent edges of the partition 9 are so connected as to 85 form a triangular space 14 while in Fig. 5 the partitions are bent near their adjacent edges so as to increase the angularity of the greater portion of the partitions.

With the construction shown, a cylinder is provided in which work is subjected to a series of crowding, tumbling and squeezing actions during one rotation of the cylinder whereby the work is more efficiently cleaned with a lesser amount of treating liquid instead of being merely rolled over and over as it would be in the usual perforated cylinder having no partitions or baffles therein.

What I claim is:

1. In a machine of the class described, an outer tub for treating liquid, a load-carrying cylinder rotatably mounted in said tub and comprising end heads, an outer cylinder wall made up of a plurality of spaced sections connected to said end heads, and longitudinally extending compartment forming partitions extending radially outwardly from the center of said cylinder to one edge of each cylindrical wall section and forming angular pockets at the junction therewith, said partitions being perforated adjacent their points of connection with said wall sections whereby an opening is provided of a size to be successively covered and uncovered by the load during operation of the apparatus to retain liquid within the compartments or permit liquid to enter and exhaust from said compartments.

2. In a machine of the class described, an outer tub for treating liquid, a load-carrying cylinder rotatably mounted in said tub and comprising end heads, an outer cylinder wall made up of a plurality of spaced sections connected to said end heads, and longitudinally extending compartment forming partitions extending radially outwardly from

the center of said cylinder to one edge of each cylindrical wall section and forming angular pockets at the junction therewith, said partitions being perforated adjacent their points of connection with said wall sections and perforated sheets connecting each of said partitions with the next adjacent wall section whereby an opening is provided through which liquid may enter and exhaust from said compartments.

3. In a machine of the class described, an outer tub for treating liquid, a load-carrying cylinder rotatably mounted in said tub and comprising end heads, an outer cylinder wall made up of a plurality of sections connected to said end heads to form longitudinal openings in the cylinder wall, and longitudinally extending compartment forming partitions extending radially outwardly from the center of said cylinder to one edge of each cylindrical wall section and forming angular pockets at the junction therewith, said partitions being perforated adjacent their points of connection with said wall sections and perforated sheets connecting each of said partitions with the next adjacent wall section whereby V-shaped openings are provided through which liquid may enter and exhaust from said compartments.

4. In a machine of the class described, an outer tub for treating liquid, a load-carrying cylinder rotatably mounted in said tub and comprising end heads, an outer cylinder wall made up of a plurality of sections connected to said end heads, longitudinally extending compartment forming partitions extending radially outwardly from the center of said cylinder to one edge of each cylindrical wall section, perforated plates cooperating with said partitions and said cylindrical wall sections to form angular pockets opening through the arcuate wall, said partitions being perforated adjacent their points of connection with said wall sections, and single baffle means carried by each partition that is spaced from but adjacent to the center of the cylinder.

In testimony whereof I hereby affix my signature.

FRITZ BALZER.
